UNITED STATES PATENT OFFICE.

GEORGE LAWSON HERRIN, OF MOUNT PLEASANT, NORTH CAROLINA.

HEATER FOR CARBURETORS.

Application filed October 18, 1919. Serial No. 331,545.

To all whom it may concern:

Be it known that I, GEORGE LAWSON HERRIN, a citizen of the United States, residing at Mount Pleasant, in the county of Cabarrus and State of North Carolina, have invented new and useful Improvements in Heaters for Carburetors, of which the following is a specification.

This invention relates to attachments for internal combustion engines and has for its object the provision of a heating drum associated with and surrounding a part of the carburetor and receiving heat from the exhaust of the engine, the purpose of the device being to heat the gasoline within the carburetor so that the gasoline may be more readily converted into vapor and whereby a very efficient and more easily exploded mixture will be produced.

An important object is the provision of a device of this character which is in the nature of a drum encircling the bowl of a carburetor and provided with clamping means whereby it may be secured upon the carburetor.

Another object is the provision of a device of this character which is provided with a tube extending from the drum into the carburetor whereby to introduce exhaust gas within the carburetor.

An additional object is the provision of a device of this character which will be simple and inexpensive in manufacture, easy to install, efficient and fuel saving in use, durable in service, and a general improvement in the art.

With the above and other objects and advantages in view, the invention consists in the details of construction to be hereinafter more fully described and claimed and illustrated in the accompanying drawings in which—

Figure 1 is a side elevation of a motor and carburetor showing my device in position,

Figure 2 is a plan view of a carburetor showing the device in position,

Figure 3 is a cross sectional view showing the carburetor in elevation,

Figure 4 is a plan view of my device detailed,

Figure 5 is a side elevation thereof.

Referring more particularly to the drawings, the letter A designates an internal combustion engine of the type used upon a very popular make of automobile, B des-

ignates the exhaust manifold, and C designates the carburetor.

In carrying out my invention I provide a circular drum 10 which is formed as a ring-like member which is hollow and the inner periphery of this drum is of such size as to snugly receive or engage upon the bowl of the carburetor C with the top surface of the drum flush with the top of the bowl. The drum is secured in position by means of a plurality of clips 11 which are secured upon the upper edge of the drum by suitable screws 12 which project over and engage upon the top of the bowl.

At one side the drum is provided with a boss 13 which is threaded and adapted to be connected by a coupling 15 to a pipe 16 which leads into the exhaust manifold.

In order to introduce exhaust gas within the carburetor I provide a tube 17, which has one end extending into the drum 10 at its upper edge and which has its other end extending into the upper portion of the carburetor and it is preferable that this tube be provided with a cut-off valve 18 whereby passage of exhaust gas from the drum into the carburetor may be regulated at will or cut off entirely.

In the operation of the device it will be seen that as the tube 16 leads into the exhaust manifold, some of the burned gases will pass through the tube 16 into the drum and effect heating of the carburetor. It will also be apparent that when the valve 18 is open the exhaust gases within the drum 10 will pass into the carburetor and be mixed with the vaporized gasoline therein whereby to form a more efficient and more highly explosive mixture than if only cold air were admitted.

From the foregoing description and a study of the drawings it will be apparent that I have thus provided a very simple and inexpensive heating drum attachment for carburetors which will effectually heat the gasoline vaporized and which will consequently economize on fuel as it is well known that a hot mixture explodes more readily and gives more power than a cold mixture. It will also be apparent that the device may be readily attached and that it will efficiently perform all the functions for which it is intended.

While I have shown and described the

preferred embodiment of my invention, it is of course to be understood that I reserve the right to make such changes in the form, construction, and arrangement of parts as 5 will not depart from the spirit of the invention or the scope of the subjoined claims.

Having thus described my invention, I claim:

1. In combination with the exhaust manifold and carburetor of an internal combustion engine, means for heating the carburetor comprising a hollow ring-like drum disposed in encircling relation to the carburetor, a plurality of clips pivotally mounted upon 10 the top of said drum and engageable over the upper edge of the carburetor bowl, a

pipe connected with one side of the drum and connected with the exhaust manifold, and a valved tube for effecting communication between said drum and the carburetor. 20

2. In combination with the exhaust manifold and carburetor of an internal combustion engine, means for heating the carburetor comprising an integral hollow ring shaped drum disposed in encircling relation 25 to the carburetor bowl, a plurality of clips pivoted upon said drum and engaging over the top of the carburetor bowl, and a pipe connected with said drum and connected with the exhaust manifold. 30

In testimony whereof I affix my signature.
GEORGE LAWSON HERRIN.
